BURNER ASSEMBLY FOR SPACE HEATER

Erwin D. Cado, Chicago, Oliver B. Buskirk, La Grange, and Herschel A. Setser, Chicago, Ill., assignors to Motorola, Inc., Chicago, Ill., a corporation of Illinois

Application August 19, 1952, Serial No. 305,176

7 Claims. (Cl. 158—53)

The present invention relates to air space heaters of the type consuming liquid fuel such as gasoline or kerosene, and more particularly to a burner assembly for use in such a heater enabling the heater to provide adequate heat for a space of moderate size such as a house or a cottage.

The major requirements for heaters of the above-mentioned type are that they be inconspicuously small, have a compact, simple and relatively inexpensive construction, and be capable of generating adequate heat. Liquid fuel burning heaters are known to the art in which a volume of liquid fuel is burned directly at its surface or is fed by a wick to a combustion chamber. This type of heater is not generally satisfactory for the above-mentioned purpose because the burner structure is large in proportion to the heat obtainable therefrom, and the burner usually requires a chimney to create the necessary draft. Another type of known liquid fuel burner is one in which liquid fuel is atomized by a high pressure air jet prior to its application to the combustion chamber. This produces a combustible spray of fuel in the combustion chamber that may be ignited to effectuate the heating process. However, the latter arrangement requires a relatively large amount of power to carry out the atomizing process and is practical only in large installations. Yet another type of liquid fuel burner is known in which the fuel is vaporized and mixed with air in a heated conditioning chamber prior to ignition. A combustible mixture is formed in the conditioning chamber which is supplied to the burner ports adjacent the combustion chamber of the heater to be ignited and burned. This arrangement is advantageous since the power requirement is low, its efficiency is high, and its necessary components are relatively simple and inexpensive and may be arranged in a compact assembly. However, although such a heater has been used to some extent in automobiles and other vehicles, its use for domestic and household purposes has been rather limited due to the relatively high heat requirements of the latter. It is also preferable for domestic requirements to use a low volatile fuel such as kerosene rather than gasoline, and this has aggravated the problem since such fuels have a certain maximum vaporization temperature and it has proved difficult to maintain that temperature within the conditioning chamber and yet provide sufficient heat to the space to be heated.

Copending application Serial No. 52,169, filed October 1, 1948, in the name of Stanley J. Budlane, entitled "Heater," and assigned to the present assignee, which issued as Patent 2,673,558 on March 30, 1954, discloses and claims a heater utilizing the afore-described vaporizing principles of fuel conditioning, and which is constructed to overcome the afore-mentioned problems so as to be eminently suitable for household purposes. The heater disclosed in the Budlane application achieves a relatively stable temperature for fuel vaporization and produces a high amount of heat even though a low

volatile fuel is used. The fuel conditioning chamber in the Budlane arrangement is maintained at the optimum vaporization temperature for the particular fuel utilized by redirecting a pilot flame, normally used to ignite the main burners, back against the conditioning chamber. Moreover, in order that the temperature of the conditioning chamber will not exceed the optimum vaporizing temperature of the fuel utilized, as one or more main burners are brought into operation, the heater is constructed so that heat from the main burners is directed away from the fuel conditioning chamber and that chamber continues to derive its heat solely from the pilot flame. However, it has been found in the Budlane arrangement that under some conditions it is difficult to insulate completely the conditioning chamber from the main burners so as to maintain the chamber at the optimum vaporizing temperature when the main burners are in operation.

The present invention constitutes an improvement over the arrangement disclosed in the Budlane application, and its principal object is to provide an improved burner assembly for a liquid fuel consuming heater which is constructed so that even though the temperature of the conditioning chamber exceeds the optimum vaporizing temperature for the fuel utilized when the heater is in operation, the burner assembly is so constructed that fuel vaporization continues to be carried on at the optimum temperature and fuel sputtering and cracking is prevented.

A general object of the invention is to provide a new and improved burner assembly for use in a fuel burning air heater which may utilize a low volatile fuel, and which enables the heater to generate more heat than has been heretofore considered possible without adversely affecting the vaporizing process of the fuel.

The features of the invention which are believed to be new are set forth with particularity in the appended claims. The invention itself, however, together with further objects and advantages thereof, may best be understood by reference to the following description when taken in conjunction with the accompanying drawings in which:

Fig. 1 shows the complete heater unit mounted in an appropriate casing;

Fig. 2 shows a front view of the heater with the housing removed;

Fig. 3 shows a side view of the heater partially in section;

Fig. 4 is a top view of the heater;

Fig. 5 is a sectional view of the burner assembly of the heater taken along the line 5—5 of Fig. 3;

Fig. 6 is a sectional view of a component of the burner assembly taken along the line 6—6 of Fig. 5;

Fig. 7 is a front view of a vaporizing block used in the burner assembly;

Fig. 8 is a sectional view of the vaporizing block taken along the line 8—8 of Fig. 7;

Fig. 9 is a temperature-equalizing plate utilized in the burner assembly;

Fig. 10 is a top view of the plate shown in Fig. 9;

Fig. 11 is a side view, partially in section, of the heater unit showing only certain components of the heater; and

Figs. 12 and 13, respectively, show perspective and front views of a refractory unit utilized in the burner assembly.

The burner assembly of this invention is for use in a fuel burning air heater and includes in combination a heat conductive body having at least one main fuel vaporizing passage extending therethrough terminating at the front of the body in a main burner port, and having a pilot fuel vaporizing passage extending therethrough and terminating at the front of the body in a pilot burner

port adjacent the main burner port. A refractory unit engages the front of the aforesaid body and has at least one combustion passage extending therethrough along a transverse axis with respect to the front of the body, and also has an inner wall facing the pilot burner port and spaced from the front of the body to define with the front of the body and with the sides of the refractory unit a baffle chamber. The wall in the refractory unit has an opening therein facing the main burner port and communicating with the combustion passage. Finally, a heat conductive secondary fuel vaporizing shelf member is disposed within each of the fuel vaporizing passages but heat-insulated from the aforesaid body so that a temperature differential exists between each shelf and the body. The liquid fuel is supplied to the secondary fuel vaporizing shelves and efficient vaporization is achieved in a manner to be described, even though the temperature of the aforesaid body and of the surfaces of the fuel vaporizing passages themselves exceed the optimum vaporizing temperature of the fuel utilized.

As shown in Fig. 1, the heater is enclosed in a steel cabinet 10, which has a baked enamel finish on its outer surface. Circulating air inlet louvers 11 are formed at each side of the cabinet and at the bottom, and these louvers are preferably equipped with aluminum-mesh air filters inside the cabinet. A circulating air outlet louver 12 is formed in the top of the cabinet. Circulating air is drawn in through the inlet louvers, heated and forced out through the outlet louver in a manner to be described. The unit also includes a temperature control knob 13 at the top, and also a humidifier cap 14 through which water may be poured into a humidifier can mounted in the interior of the housing 10.

With reference now primarily to Figs. 2-5, the heater unit includes a vertical mounting plate 15 adapted to be supported by a wall or the like. A horizontal shelf 16 having a central orifice 16a is supported by the mounting plate, and an air circulating fan 17 is disposed in the orifice. As disclosed and claimed in copending application Serial No. 305,132 filed August 19, 1952, in the name of Edward A. Salners et al. entitled Liquid Fuel Burning Heater Assembly, and assigned to the present assignee, fan 17 is supported and driven by a vertically disposed motor 18 supported on a mounting bracket 19 which, in turn, is rigidly supported on the top of a cylindrical combustion fan housing 20 by studs 21a, 21b and 21c. Housing 20 contains a combustion air fan 17a which is also supported and driven by motor 18. The bottom of housing 20 is flat with a central aperture through which the combustion fan draws the air to be supplied to the heater assembly portion of the heater. Housing 20 rests on a shock mount 22 and further shock mounts (not shown) resting in brackets such as bracket 23 secured to a cylindrical air header 24. The air header is supported by mounting plate 15 and communicates with an inlet air duct 25 secured to and extending down the back of the mounting plate. Header 24 has an apertured top portion and is flexibly coupled to the aperture or orifice in the bottom of housing 20 by means of a flexible coupling comprising a pair of annular members 25a, 26 in respective frictional engagement with the orifices in housing 20 and header 24. Members 25a and 26 are intercoupled by an airtight flexible bellows 27 extending therebetween. Housing 20 is also flexibly coupled to a transition piece 28 rigidly secured to mounting plate 15, and communicating through the mounting plate with a further duct 33 leading up the back of the plate adjacent duct 25 to the combustion assembly of the heater. The housing 20, therefore, provides a floating mounting for motor 18 so that vibrations of the motor are not communicated to the assembly as a whole.

The heater includes a heat control unit 29 mounted to plate 15 below shelf 16 and adjacent fan housing 20. The heat control unit includes a main switch for completing an energizing circuit to the heater, and also in-

cludes further switches controlling the application of fuel to the main burners of the heater, the further switches being responsive to ambient temperature variations and being set manually so as to establish a desired temperature within the space to be heated. Unit 29 is controlled by means of a control rod 30 rotatably supported on mounting plate 15 by a bracket 31 and extending to the unit from the aforementioned control knob 13. The heat control unit is described in detail in aforementioned copending application Serial No. 305,132 filed August 19, 1952, in the name of Edward A. Salners et al., entitled Liquid Fuel Burning Heater Assembly, assigned to the present assignee, and a further description herein is deemed unnecessary as this unit, per se, forms no part of the present invention.

The power supply unit for the heater is indicated generally as 32, and is supported by plate 15 below shelf 16 adjacent control unit 29. Details of the power supply unit and of the electrical connections thereto may also be found in the above-mentioned copending application.

A humidifier tank 35 is secured to plate 15 above the shelf 16 and has an open top in communication with plug 14 of Fig. 1, so that water may be added to the humidifier from time to time.

A rectangular shaped inlet air duct 36 extends through and is supported by plate 15, and this duct communicates with transition piece 28 of combustion fan housing 20 by means of duct 33 secured to and extending down the back of plate 15 adjacent duct 25 as mentioned previously herein. A circular exhaust duct 37 also extends through and is supported by plate 15, and the exhaust duct communicates with an exhaust pipe 37a extending from the back of the plate. A fuel metering unit base 38 is supported at the top of air duct 36 and has a series of solenoid operated fuel metering valves 39-42 mounted thereon and extending into its interior. A fuel pump 43 is supported on a bracket 44 extending from the back of base 38, and fuel such as kerosene, gasoline or the like is supplied to the pump by a fuel line 45 extending thereto from a filter unit 46 supported by the line. The fuel is supplied to the filter unit by an inlet fuel line (not shown) extending from the back of the filter and through mounting plate 15 to an appropriate fuel tank. A surge chamber 47 also communicates with filter 46 and functions in well-known fashion. Fuel from the pump is supplied by a line 48 to a pressure regulator 49, and fuel from the pressure regulator is supplied to the interior of base 59. The fuel metering unit and pump assembly may be similar to that disclosed in copending application Serial No. 305,120 filed August 19, 1952, in the name of Jerome G. Zahradka entitled "Heater," assigned to the present assignee, and a detailed description herein is deemed unnecessary.

The burner assembly of the heater is best shown in Fig. 3 and comprises a vertical mounting plate 60 supported by air duct 36 and exhaust duct 37. A casting 61 is secured to mounting plate 60 and surrounds the end of air inlet duct 36. A fuel vaporizing block 62 of heat conductive material is secured to casting 61 with a temperature-equalizing plate 63 interposed therebetween, the temperature-equalizing plate and casting 61 forming a plenum chamber 64 into which air from duct 36 is supplied.

Fuel vaporizing block 62 has a pair of parallel main fuel vaporizing passages 65 and 66 extending therethrough one above the other and terminating respectively at the front of the block in main burner ports 67 and 68. The main burner fuel vaporizing passages 65 and 66 communicate with plenum chamber 64 through respective apertures 69 and 70 in temperature-equalizing plate 63 (Fig. 9). Vaporizing block 62 also has a pilot burner fuel vaporizing passage 71 extending therethrough between the main burner passages, the pilot burner passage terminating in a pilot burner port 72 at the front of the block and communicating at the back of the block with

plenum chamber 64, through a hole 73 in temperature-equalizing plate 63. The vaporizing block has further passages 74 and 75 extending therethrough, for reasons to be explained, and terminating respectively in the front of the block in apertures 76 and 77 and communicating with plenum chamber 64 through respective apertures 73 and 79 in plate 63. Vaporizing block 62 has still further passages (Fig. 7) 80, 81 extending from the front of the block part way therethrough and then terminating at each side thereof (see also Fig. 8).

Temperature-equalizing plate 63 supports a series of shelves 82, 83 and 84 which are disposed respectively in the main burner passages 65, 66 and in the pilot burner passage 71 of burner block 62; these shelves constituting secondary vaporizing surfaces within these passages. The secondary vaporizing shelves are composed of a heat conductive material such as a nickel alloy and are supported by plate 63. Plate 63 is sandwiched between a pair of heat insulating gaskets 63a and 63b in order that the shelves may be heat insulated to some extent from block 62 so that a temperature differential is established between the shelves and the surfaces of the passages, the temperature of the shelves being equalized by plate 63. Each shelf has a multiplicity of apertures formed therein with burred edges contacting the bottom surfaces of the respective passages.

An igniter unit 90 (Figs. 5 and 11) is supported at one side of air duct 36 in the inclined position shown in those figures. As shown in Fig. 6 the igniter unit comprises a cylindrical housing 91 which communicates with a tube 92 extending at right angles thereto and through a flame directing passage 93 in casting 61 and vaporizing block 62. Tube 92 also serves to support the igniter 90, and further support is provided for the igniter by a chamber 126 secured to air duct 36 and base 38. Chamber 126 has an aperture 125 communicating with the interior of the air duct and an aperture 127 communicating with the interior of igniter 90. The flame directing passage 93 terminates at the front of the vaporizing block adjacent pilot burner port 72 as best shown in Fig. 7. Tube 92 extends through an aperture 94 in temperature-equalizing plate 63 as shown in Fig. 9. As shown in Figs. 5 and 6, the igniter unit comprises an electrical heating element 95 centrally disposed within a casing 96, the surface of the latter constituting a primary vaporizing surface for the igniter. Electrical contact is made to the igniter element through a stud 97 and the circuit is completed at the other end of the element by a strip 98 connecting the element to casing 96 which is at ground potential. A mesh screen 97 surrounds a portion of casing 96 and may be composed of a nickel alloy or other heat conductive material which by virtue of its mesh construction is heat insulated to some extent from casing 96 and maintained at a lower temperature than the casing.

A solid refractory unit 100 (Fig. 3 and Figs. 12, 13) engages the front of vaporizer block 62 and has a pair of spaced parallel combustion passages 101 and 102 extending therethrough one above the other along transverse axes with respect to the front of the vaporizing block. The refractory unit has an inner wall 103 facing the pilot burner port 72 and spaced from the front of the vaporizing block to define with the front of the block and with the sides of the refractory unit a baffle chamber. The inner wall has a pair of openings therein at the top and bottom thereof respectively facing main burner ports 67 and 68 and each communicating with a different one of the combustion passages 104, 105. In this manner, practically all the heat from the main burners is directed into combustion passages 101 and 102 and has little effect on the temperature of the vaporizing block 62.

As previously stated, fuel pump 43 supplies liquid fuel to base 38 of the fuel metering unit through pressure regulator 49. Liquid fuel from the interior of base 38 is supplied to igniter 90 through fuel line 110 upon actuation of solenoid valve 42. Likewise, liquid fuel is sup-

plied to the main burner passages 65 and 66 through fuel lines 111 and 112 upon actuation of solenoid valves 39 and 40 respectively, and to pilot burner passage 71 through fuel line 113 upon actuation of solenoid valve 41.

The burner assembly is enclosed in a housing or casing 115 which communicates with exhaust duct 37 as shown in Fig. 3. The casing also supports a heat exchanger 116 which extends laterally from either side of the casing. Portions 116a and 116b of the heat exchanger each enclose a passage which communicates with passages 101 and 102 of refractory unit 100, and portions 116c and 116d of the heat exchanger enclose passages which communicate with the interior of casing 115 (Fig. 6) and therefore with exhaust duct 37.

To place the heater unit in operation knob 13 is turned to an "on" position which closes a main switch in unit 29 so that motor 18 is energized and fans 17 and 17a are actuated. Fan 17 draws circulating air in through louvers 11 and drives it through orifice 16a in plate 16 up past the heat exchanger 116 and out through outlet louvers 12. At the same time, combustion fan 17a draws combustion air in through an air inlet pipe 36a which is mounted to the rear of the unit coaxially with exhaust pipe 37a, the combustion air being drawn down duct 25 into header 24 and forced out transition piece 28 up duct 33 and through air duct 36 into plenum chamber 64. Air from the plenum chamber is forced through temperature-equalizing plate 63 to the main and pilot burner passages 65, 66 and 71 in vaporizing block 62. Air is also supplied to igniter unit 90 through aperture 125 in air duct 36 and through chamber 126 into aperture 127 in casing 91 of the igniter unit. The igniter electrical element 95 is then energized so that primary vaporizing surface 96 is heated, as is secondary vaporizing surface 97 which is constituted by the aforementioned wire screen. Solenoid valve 42 is then energized so that fuel is supplied to the igniter through fuel line 110. The fuel line terminates adjacent screen 97 so that fuel is dropped onto the screen. When the igniter is in a relatively cool condition, the fuel passes through the screen and is vaporized by the primary vaporizing surface of casing 96. The vaporized fuel mixes with the air to form a combustible mixture which is ignited by electrically-heated strip 98 so that an igniter flame is produced in tube 92 and in flame-directing passage 93 in the vaporizing block 62 initially heating the block. Should surface 96 be heated beyond the optimum vaporizing temperature of the fuel used, screen 97 is heated to a lower temperature thereby due to its heat insulating relation with that surface, and the screen reaches a vaporizing temperature so that the fuel is vaporized upon contact therewith and does not reach surface 96. In this manner, the fuel continues to be vaporized at its optimum vaporizing temperature even though the heater element has caused surface 96 to exceed that temperature.

When the flame in passageway 93 heats the vaporizing block to a selected temperature, solenoid 41 is energized so that fuel is supplied to pilot burner passage 71 through fuel line 113. The fuel line terminates at shelf 84 and when the vaporizing block is in a relatively cool condition, the fuel passes through the apertures in the shelf to the base of passage 71, which base constitutes a primary vaporizing surface. The apertures are formed in the shelves with burred edges preferably in contact with the bottom of the various passages to obviate the formation of fuel on the top of the shelves due to surface tension. The vaporized fuel in the pilot burner passage is mixed with the air therein to form a combustible mixture at pilot burner port 72 which is ignited by the igniter flame from flame directing passage 93. The resulting flame from the pilot burner is directed against wall 103 of refractory unit 100 and redirected thereby back against vaporizing block 62 and into passages 74, 75, 80 and 81, so that the entire block is rapidly brought to the optimum

temperature for the fuel used. The igniter element may now be deenergized and the igniter flame discontinued.

Fuel-metering solenoid valves 39 and 40 may now be energized and fuel supplied onto shelves 82 and 83 in the main burner passages 65 and 66. The fuel passes through the apertures in shelves 82 and 83, and is vaporized at the base of the respective passages (which bases constitute primary fuel vaporizing surfaces) and is mixed with air from plenum chamber 64. The resulting combustible mixture is ignited at the main burner ports by the pilot flame, and the resulting main burner flames are directed tangentially into combustion passages 101 and 102 in which a swirling action is set up. The resulting combustion products are directed through passages 116a and 116b of heat exchanger 116 and back to the interior of casing 115 through heat exchanger passages 116c and 116d and, thence, out through exhaust duct 37 and exhaust pipe 37a. The actuation of solenoid valves 39 and 40 is controlled by unit 29 in the manner fully described in the aforementioned copending application Serial No. 305,132 filed August 19, 1952 in the name of Edward A. Salners et al. entitled Liquid Fuel Burning Heater Assembly, so that the heater may be adjusted to maintain the space to be heated at any desired ambient temperature.

When the main burners have been in operation for some time, it is possible under some circumstances (despite the configuration of unit 100) for the temperature of the vaporizing block to rise above the optimum vaporizing temperature of the fuel utilized. When that occurs, shelves 82, 83 and 84 are heated to such vaporizing temperature so that fuel no longer passes through the shelves to the primary vaporizing surfaces, but is vaporized by the shelves themselves. In this manner, due to the temperature differential between the shelves and block 62, the fuel continues to be vaporized at its optimum vaporizing temperature even though the vaporizing block itself is at a higher temperature, and spluttering and cracking of the fuel is thereby prevented.

The invention provides, therefore, an improved heater unit having extremely high heat capabilities and yet which operates with a high degree of efficiency. By use of the present invention the heat output of the heater can be such that the temperature of the vaporizing block rises above the optimum vaporizing temperature of the fuel utilized. Yet, due to the action of secondary vaporizing shelves, the fuel continues to be vaporized at its optimum vaporizing temperature. Moreover, due to the configuration of the combustion chamber unit, maximum heat is obtained from the main burners with minimum effect on the vaporizing block.

While a particular embodiment of the invention has been shown and described, modifications may be made, and it is intended in the appended claims to cover all such modifications as fall within the true spirit and scope of the invention.

We claim:

1. A burner assembly for use in a fuel burning air heater including in combination: a heat conductive block having at least one main fuel vaporizing passage extending therethrough terminating at the front of said block in a main burner port, and having a pilot fuel vaporizing passage extending therethrough and terminating at the front of said block in a pilot burner port adjacent said main burner port; means to supply fuel and air to said main fuel vaporizing passage and to said pilot fuel vaporizing passage; and a separate body engaging the front of said block having at least one combustion passage extending therethrough spaced from the front of said block and along a transverse axis with respect to the front of said block, and further having an inner wall between the combustion passage and the front of said block facing said pilot burner port and spaced from the front of said block to define with the front of said block and with the sides of said body a baffle chamber, and said wall having an opening therein facing said main burner port and communicating with said combustion passage; a heat conductive secondary fuel-vaporizing shelf member disposed within each of said fuel-vaporizing passages and supported in heat insulated relation from said block, and fuel supply means to introduce fuel on each of the shelf members so that vaporization of fuel permits a temperature differential between said heat conductive block and said shelf member upon heating of said block for efficient combustion of fuel in said burner assembly.

2. A burner assembly for use in a fuel burning air heater including in combination: a heat conductive block having a pair of horizontal, parallel main fuel vaporizing passages extending therethrough mutually spaced one above the other and each terminating at the front of said block in a main burner port, and having a pilot fuel vaporizing passage extending therethrough parallel to and between said main burner passages and terminating at the front of said block in a pilot burner port between said main burner ports; means to supply fuel and air to said main fuel vaporizing passages and to said pilot fuel vaporizing passage; and a separate refractory body engaging the front of said block having a pair of spaced parallel combustion passages extending therethrough spaced from the front of said block one above the other along transverse axes with respect to the front of said block, and further having an inner wall between said combustion passages and the front of said block facing said pilot burner port and spaced from the front of said block to define with the front of said block and with the sides of said body a baffle chamber, and said wall having a pair of openings therein at the top and bottom thereof respectively facing said main burner ports and each communicating with a different one of said combustion passages whereby fuel and air conducted through said pilot burner port are burned in said baffle chamber and fuel and air conducted through said main burner ports are burned in said combustion passages.

3. A burner assembly for use in a fuel burning air heater including in combination: a heat conductive block having at least one main fuel vaporizing passage extending therethrough terminating at the front of said block in a main burner port and having a pilot fuel vaporizing passage extending therethrough and terminating at the front of said block in a pilot burner port adjacent said main burner port; means to supply air to said main fuel vaporizing passage and to said pilot fuel vaporizing passage; a separate refractory body engaging the front of said block having at least one combustion passage extending therethrough spaced from the front of said block along a transverse axis with respect to the front of said block, and further having an inner wall between said combustion passage and the front of said block facing said pilot burner port and spaced from the front of said block to define with the front of said block and with the sides of said body a baffle chamber, and said wall having an opening therein facing said main burner port and communicating with said combustion passage; a heat conductive secondary fuel-vaporizing shelf member disposed within each of said fuel-vaporizing passages and supported in heat insulated relation from said block, and fuel supply means to introduce fuel on each of the shelf members so that vaporization of fuel permits a temperature differential between said heat conductive block and said shelf member upon heating of said block for efficient combustion of fuel in said burner assembly.

4. A liquid-fuel burning air heater including in combination: a heat conductive body having at least one main fuel vaporizing passage extending therethrough terminating at the front of said body in a main burner port, and having a pilot fuel vaporizing passage extending therethrough and terminating at the front of said body in a pilot burner port adjacent said main burner port, the walls of said passages constituting primary fuel-vaporizing surfaces; respective fuel lines extending to said passages for supplying liquid fuel thereto; means for supplying air under pressure to said passages; and a heat conductive plate; heat insulating means for securing said plate to the back of said body in limited heat conductive relation.

tion therewith; heat conductive apertured fuel vaporizing shelf members supported by said plate and respectively disposed within said passages in spaced relation with the primary fuel vaporizing surfaces and at the ends of respective ones of said fuel lines for receiving liquid fuel therefrom, said shelf members constituting secondary fuel-vaporizing surfaces and being adapted to be maintained at a lower temperature than said body upon heating of said body, and said shelf members passing fuel through the apertures therein to said primary vaporizing surfaces when said second vaporizing surfaces are below the vaporizing temperature.

5. A burner assembly for use in a fuel burning air heater including in combination: a heat conductive block having at least one main fuel vaporizing passage extending therethrough terminating at the front of said block in a main burner port, having a pilot fuel vaporizing passage extending therethrough and terminating at the front of said block in a pilot burner port adjacent said main burner port, and further having an igniting flame directing passage extending therethrough and terminating adjacent said pilot burner port; a fuel consuming igniter unit communicating with said flame-directing passage; respective fuel lines extending to said vaporizing passages and said igniter unit for supplying liquid fuel thereto; means for supplying air under pressure to said passages; and a separate refractory body engaging the front of said block having at least one combustion passage extending therethrough spaced from the front of said block along a transverse axis with respect to the front of said block, and further having an inner wall between said combustion passage and the front of said block facing said pilot burner port and spaced from the front of said block to define with the front of said block and with the sides of said body a baffle chamber, and said wall having an opening therein facing said main burner port and communicating with said combustion passage.

6. A burner assembly for use in a liquid fuel burning air heater including in combination: a walled heat conductive body having a plurality of fuel vaporizing passages extending therethrough and terminating at the front of said body in respective burner ports, the walls of said passages defining primary fuel-vaporizing surfaces; a temperature-equalizing plate means secured to the back of said body in limited heat-conductive relation therewith, said plate having apertures registering with and forming inlets to said passages; means to supply air to said vaporizing passages; a plurality of apertured heat

conductive fuel vaporizing shelf members supported by said equalizing plate means and extending into said respective passages in spaced relation with the respective primary fuel-vaporizing surfaces; and means to introduce fuel on said shelf members to thereby maintain the shelf members at a lower temperature than said body due to vaporization of fuel thereon, so that vaporizing occurs at optimum temperature and fuel from said burner ports burns efficiently.

7. A burner assembly for use in a liquid fuel burning air heater including in combination: a walled heat conductive body having at least one fuel vaporizing passage extending therethrough and terminating at the front of said body in a burner port, the walls of said passage defining primary fuel-vaporizing surfaces; plate means; heat insulating means for securing said plate means to the back of said body in limited heat-conductive contact therewith, said plate means having apertures registering with and forming inlets to said passage; means to supply air to said vaporizing passage; a heat-conductive fuel-vaporizing shelf member supported by said plate means and extending into said passage in spaced relation with the primary fuel vaporizing surface; and means to introduce fuel on said shelf member to thereby maintain the shelf member at a lower temperature than said primary fuel vaporizing surface due to vaporization of fuel thereon, said shelf member constituting a secondary fuel-vaporizing surface and having a multiplicity of apertures therein to allow fuel to flow to said primary vaporizing surface when said secondary vaporizing surface is below the vaporizing temperature and said multiplicity of apertures each having burred edges coacting with the bottom of said passage to prevent the formation of excess liquid fuel on said shelf due to surface tension.
